UNITED STATES PATENT OFFICE.

RUDOLF EICKEMEYER, OF YONKERS, NEW YORK.

MAGNETO-ELECTRIC AND ELECTRO-MAGNETIC MACHINE.

SPECIFICATION forming part of Letters Patent No. 351,903, dated November 2, 1886.

Original application filed November 8, 1882. Serial No. 76,234. Divided and this application filed December 26, 1884. Serial No. 151,178. (No model.)

To all whom it may concern:

Be it known that I, RUDOLF EICKEMEYER, of Yonkers, in the county of Westchester and State of New York, have invented certain new and useful Improvements in Magneto-Electric and Electro-Magnetic Machines; and I do hereby declare that the following specification, taken in connection with the drawings furnished and forming a part thereof, is a clear, true, and complete description of the several features of my invention.

It is to be understood that the machine hereinafter particularly described and illustrated in the drawings embodies certain features of my invention which have been broadly claimed by me in my application for Letters Patent filed November 8, 1882, Serial No. 76,234, and that in my said application I have shown and described in detail the machine which constitutes the subject of this application, which is now filed as a division of said prior application.

My present improvements relate to what are known as "unipolar machines."

The characteristic feature of a machine embodying my present improvements is an armature or electric-generator element, which embodies iron or steel, which is polarized in the line of the armature-axis, and is inclosed by but free to revolve within a polarized mass of iron, and so organized that it constitutes a portion of the magnetic circuit of the machine. I have also so constructed the armature or electric-generator element that it serves not only as a portion of the magnetic system of the machine, but also as an electric conductor. I have also so constructed and organized the armature or electric-generator element as to render it a compound magnet embodying a series of bar-magnets, and each of these also serves as an electric conductor, and they are electrically connected by me so as to provide for a continuous electric circuit, including all of said bar-magnets or any lesser number thereof, as may be desired. I have also so constructed and organized the magnetic portions of the machine that the outer magnet is double; or, in other words, it embodies two magnets, and also so that the armature embodies two or more magnets, there being therein a number of bar-magnets, each of which is dou-

ble, having corresponding poles at its two ends, and a central consequent pole.

The several features of my invention which I propose to include in this application will be specified in the several clauses of claims hereunto annexed, and a practically valuable embodiment of all of said improvements will be described in connection with a machine illustrated in the drawings, in which—

Figure 1 is a longitudinal horizontal section of said machine. Fig. 2 is a vertical cross-section of the same on line *x*. Fig. 3, in two views, illustrates one of several conducting-rings which are employed on the armature or electric-generating element. Fig. 4, in two views, illustrates one of several flanged rings composed of hard rubber or other insulating material, and which are interposed between the conducting-rings, Fig. 3, when mounted in position on the armature.

A mass of iron cylindrically chambered is polarized to constitute it a tubular magnet, *A*, having at each end a helix, *B*, said helices being so wound as to correspondingly polarize the two of said ends and afford a consequent central pole. As here shown, both ends of said tubular magnet are polarized, *N*, thus affording the central pole, *S*, as clearly indicated. This tubular magnet is cast in two counter parts, bolted together, as clearly shown in Fig. 2, and it is provided with a base-flange, by which it can be properly mounted upon a suitable platform. The tubular magnet *A*, at each end, is also internally recessed angularly for the reception of the helices *B*, and near the inner end of each helix the upper wall of the tubular magnet is cut away, as at *a*, for affording access to certain conducting-rings, to be hereinafter described.

Within the polarized mass of metal which constitutes the magnet *A* is a revolving armature or rotative electric-generating element, *C*, which is provided with a central shaft, *b*, mounted in suitable boxes, *c*, and also provided with a pulley (not shown) or other means by which it may be rotatively coupled to other mechanism. This armature *C* extends throughout the length of the outer or tubular magnet, and as it is mainly composed of iron, magnetic poles are developed therein. As here shown, both ends are polarized, *S*, and it therefore has

a consequent central N pole, and it is therefore a cylindrical double magnet polarized in the line of the armature-axis, inclosed by an outer or tubular double magnet, these two being so organized that both are included in the same magnetic circuits, the N pole of the inner magnet being opposite the S pole of the outer magnet, and the S poles of the inner magnet being opposite to the N poles of the outer magnet.

It will be obvious that the helix at either end of the machine not only induces magnetism in the mass of metal embodied in the outer magnet, but also in the metal embodied in the generative element, and that the latter enters into and forms a part of the magnetic system, thus affording a specially effective magnetic field, and it will also be obvious that all the magnetic metal in the armature is polarized in the line of the armature-axis as distinguished from being polarized radially or at opposite sides of the armature, as in many prior machines of the bipolar variety. This magnetic armature or generative element C, for obtaining the best results, should embody a series of bars of iron, so that each bar will be a double-bar magnet, polarized as before described; and, as here shown, said armature is composed of sixteen bars, d, radially disposed around the axis or shaft b, insulated from each other and from the shaft, and secured so as to constitute a compact cylindrical structure by means of recessed clamp-plates e at each end, and clamp-nuts f, mounted on a threaded portion of the shaft b. These sixteen bar-magnets, all operating as portions of the magnetic system of the machine, also operate as conductors of the electric currents generated thereby when the machine is operated as an electric generator, and they also operate as conductors when the machine is used as a motor. It is obvious that if these bars be electrically connected at both ends of the armature a comparatively feeble current will be generated, and while such a construction would be within certain portions of my present invention, I have devised a mode of connecting said bar-magnet conductors whereby they may be electrically coupled in a great variety of arrangements.

In Fig. 3 I show one of several conducting-rings, g, which are each provided with an internally-projecting lug, g', and in Fig. 4 I show one of several insulating-rings, h, which, in cross-section, are L-shaped. These insulating-rings are accurately fitted to the exterior of the armature, and on the base portion of each a conducting-ring is mounted, and the lug g' thereof projects through a corresponding opening, h', in said insulating-ring, and is in good electric contact with its particular bar of the armature, and the projecting portion of each ring h is interposed between the conducting-ring g, mounted on its base, and the next adjacent conducting-ring, all as clearly indicated in the drawings.

In the sectional view, Fig. 1, it will be seen

that the conducting-rings g are organized in two sets or series, and that one of the bars d is electrically connected to a central ring in each set or series, and that the opposite bar d is electrically connected to the outside or end ring g of each set. It will be understood that each of the bars is similarly connected with its pairs of rings, and that each pair of rings with its bar will afford a part of an electric circuit, which may be completed by electrically connecting said rings in series—as, for instance, by an external conducting-wire and brushes, or other well-known equivalent means for electrically connecting a movable with a stationary conductor, thus enabling the machine to deliver (or receive) as many separate currents as there are bars in the interior compound magnet which serves as the armature. This same construction of compound magnet and conducting rings also enables the delivery (or receipt) of currents which traverse two or all of said bars, it being obvious that by electrically coupling the conducting-rings of each bar with the rings of the bars on each side thereof, and so on through the whole, all of said bars will be connected in linear series.

As shown in dotted lines in Fig. 1, outside conductors, i, are employed with suitable brushes for coupling the rings of one set or series with those of the other series, so that one ring of each set serves as a terminal connection, as indicated by arrows in the drawings, and it will be obvious that the currents delivered to or from the machine may be as many in number as there are bars, or that a lesser number of separate circuits can be provided for each, including a different number of bars, and therefore the currents will be correspondingly varied in their character.

Having thus described my invention, I claim as new and desire to secure under this application for Letters Patent—

1. In an electro-magnetic or magneto-electric machine, the combination, substantially as hereinbefore described, of a polarized mass of metal internally chambered and a rotative armature or generating element embodying magnetic metal polarized in the line of the armature-axis and constituting a portion of the magnetic circuit within said mass of polarized metal.

2. In an electro-magnetic or magneto-electric machine, the combination, substantially as hereinbefore described, of a polarized mass of metal internally chambered and a rotative armature embodying polarized metal which forms a portion of the magnetic circuit within said mass of metal, and also serves as an electric conductor.

3. In an electro-magnetic or magneto-electric machine, the combination, substantially as hereinbefore described, of a polarized mass of chambered metal, a rotative armature embodying magnetic metal, and one or more helices, each of which polarizes the outer mass of metal and also the metal in said armature.

4. In an electro-magnetic or magneto-elec-

tric machine, a rotating magnet polarized in the line of its axis, with a conductor attached thereto, and an inclosing-magnet, substantially as described.

5 5. In an electro-magnetic or magneto-electric machine, a rotating magnet polarized in the line of its axis with two or more conductors attached thereto and rotating therewith and connected in linear series.

10 6. In an electro-magnetic or magneto-electric machine, the combination of a rotating magnet polarized in the line of its axis, constituting an armature having two or more electric conductors connected in linear series, and an inclosing-magnet, substantially as described.

15 7. In an electro-magnetic or magneto-electric machine, a rotating compound magnet polarized in the line of its axis and acting as an armature, substantially as described.

20 8. In an electro-magnetic or magneto-electric machine, a rotating compound magnet polarized in the line of its axis and acting as an armature, and an inclosing-magnet, substantially as described.

25 9. In an electro-magnetic or magneto-electric machine, a rotating compound magnet the component parts of which are connected in linear series in an electric circuit, substantially as described.

10. In an electro-magnetic or magneto-electric machine, a rotating compound magnet the component parts of which are connected in linear series in an electric circuit, and an inclosing-magnet, substantially as described. 30

11. In an electro-magnetic or magneto-electric machine, a double magnet mounted upon or constituting a part of a rotating armature and polarized in the line of the armature-axis, substantially as described. 35

12. In an electro-magnetic or magneto-electric machine, a double magnet mounted upon or constituting a part of a rotating armature and an inclosing double magnet, substantially as described. 40

13. In an electro-magnetic or magneto-electric machine, an armature embodying a series of double-bar magnets, substantially as described. 45

14. In an electro-magnetic or magneto-electric machine, a double compound magnet serving as an armature, and a double inclosing-magnet, substantially as described. 50
